UNITED STATES PATENT OFFICE.

WILLIAM R. CRAIG, OF DE WITT, NEBRASKA, ASSIGNOR TO MARY E. CRAIG,
OF SAME PLACE.

KITCHEN-CABINET.

SPECIFICATION forming part of Letters Patent No. 258,851, dated May 30, 1882.

Application filed August 3, 1881. (Model.)

To all whom it may concern:

Be it known that I, W. R. CRAIG, of De Witt, in the county of Saline and State of Nebraska, have invented certain useful Improvements in Kitchen-Cabinets, of which the following is a specification.

This invention relates to that class of devices that combine in one several articles of kitchen or household furniture.

10 The invention consists in a novel construction and arrangement of parts, as hereinafter fully described, and pointed out in the claims.

Figure 1 is a perspective view of the cabinet with the parts open or displayed. Fig. 2 is a sectional side elevation of the same. Fig. 3 is a front elevation of a portion of the cabinet, showing the biscuit or rolling board opened or extended. Fig. 4 is a partial side elevation of the cabinet. Fig. 5 is a vertical sectional 20 elevation through sink and closet.

Similar letters of reference indicate corresponding parts.

In the drawings, A represents the base of the cabinet, on which is arranged the closet 25 B, provided with shelves a and hinged door b. At the side of the closet B is a drawer, C, of the full height of said closet B, and having secured on the under side of its bottom, on each side thereof, a rack, e, and having journaled in 30 a central aperture, d, in its bottom a roller, f, the latter being designed to facilitate the opening and closing of said drawer C, and the racks e being designed to engage with pinions g, that are journaled on a shaft, g', sunken in the base 35 A, whereby the bottom of said drawer C is kept from frictional contact with the base A, and at the same time more easily arrested at any desired point. At the side of the drawer C is another closet, D, of greater height than said 40 drawer, provided with a door, h, and designed to contain the bread-pan i or other kitchen utensils.

Above the closet and drawer B C is the biscuit or rolling board E, having racks k on its 45 reverse side, that engage in corresponding pinions, k', fixed on a shaft, k'', which is journaled above the closet and drawer B C. Said racks and pinions k k' are designed to facilitate the adjustment of said board E. On the horizontal portions of the raised ends or sides of the

said rolling-board E are formed racks l, that are designed to engage in pinions l', that are fixed on opposite ends of a shaft, l'', which is journaled above said board E, and from the back of said board E a pin, l'', projects upward, whose function is to prevent said board E from being pulled too far out by taking against the said shaft l''.

Resting on the tops of the pinions l' is the rolling-board cover F, provided with racks l''. Hence when the rolling-board E is drawn out, as shown in Figs. 2 and 3, the cover F is moved in the reverse direction inward, and when the said board E is pushed in, as shown in Fig. 4, the said cover F is moved forward and closes 65 down on the inclined portion of the ends or sides of the board E, as shown. Between the board E and cover F is sufficient room for a rolling-pin, H, as shown in Fig. 1.

Above the board and cover E F is arranged 70 the cupboard G, provided with shelves m and hinged doors G', having ventilating-openings n, covered with wire screens o.

The closet and drawer B C combined, the board E, and the cupboard G are of equal 75 width and have a common back, I, while the closet D is built, as it were, against the side of the drawer C and reacles up to about the bottom of the cupboard G. Hinged on the outer edge of the top of this closet D, so as to 80 move in a vertical plane, is the sink K, that closes up against the end or side of the cupboard G, as shown in Figs. 4 and 5, in a continuous line with the side of the closet D. Said sink K is preferably lined with sheet metal p, 85 and is provided with a discharge-pipe, q. In the lower end of this sink K, as it appears when closed, is a groove or depression, s, that is designed to retain what water may be in 90 said sink K when it is closed. A hook, L, having an offset or bend, t, in its shank and attached to said sink K, is designed to hold it in a closed position or open position. When said sink K is open the hook L engages its point over a pin, u, projecting from the back 95 I of the cabinet, as shown in Fig. 1, and when closed the offset t engages over said pin u, as shown in Fig. 5.

I am aware that cabinets somewhat resembling mine have been constructed; but I am 100

not aware that any have been made with such a convenient combination of devices and such operating mechanism as mine.

Having thus described my invention, I claim

5 as new and desire to secure by Letters Patent—

1. The combination, with the rolling-board E, provided with racks *k l*, and cover F, provided with racks *l¹*, of the pinions and shaft *l²*, substantially as herein shown and described, whereby said board and cover are simultaneously moved in opposite directions, as set forth.

2. In a kitchen-cabinet, the combination, with the closet D and the cupboard G, of the sink K, provided with the water-retaining depression *s*, hinged to the said closet and adapted to fold against the side of the cupboard, 15 substantially as and for the purpose set forth.

WILLIAM R. CRAIG.
